UNITED STATES PATENT OFFICE.

JOHN N. RICHARDSON, OF CINCINNATI, OHIO, ASSIGNOR TO THE WILLIAMSON HEATER COMPANY, OF CINCINNATI, OHIO, A CORPORATION OF OHIO.

FUEL-UNDERFEED.

1,260,056.

Specification of Letters Patent. Patented Mar. 19, 1918.

Application filed April 17, 1916. Serial No. 91,808.

To all whom it may concern:

Be it known that I, JOHN N. RICHARDSON, a citizen of the United States, and residing at Cincinnati, in the county of Hamilton and State of Ohio, have invented a new and useful Improvement in Fuel-Underfeeds, of which the following specification is a full disclosure.

My invention relates to underfeed heating furnaces and is particularly directed to a class of furnaces in which an oscillatory fuel charging cylinder is rocked from a fuel receiving position to a fuel charging position in vertical alinement with a central fuel port in the grate, together with means for forcing the fuel upwardly in stepped movements through said port.

One of the objects of my invention is to provide an improved fuel charging mechanism for forcing the charging plunger or fuel elevator upwardly in stepped movements while the cylinder is in alinement with the fuel port combined with means preventing retrograde movement of said plunger.

Another object is to provide an intermittently operated fuel charging mechanism consisting of a rack and pawl device and means functioned by a rocking of the fuel cylinder to receiving position, for disengaging the pawls to permit the charging plunger to drop, and a brake device for the rack to retard the dropping of the plunger.

In these and other features, the invention represents an improvement over the mechanism disclosed in the prior joint application of John N. Richardson and Edward A. Muller, Serial No. 846,486, filed June 22, 1914.

The features of my invention are more fully set forth in the description of the accompanying drawings, forming a part of this specification, in which:—

Figure 1 is a section through the base of the furnace showing the fuel cylinder in charging position.

Fig. 2 is a similar view showing the cylinder in fuel receiving position, with the plunger and its operating rack at the limit of fuel charging position ready to be released to lower the plunger.

Fig. 3 is a detailed view of the rack and pawl mechanism in released position.

Fig. 4 is a top plan view of the cylinder. In the drawings, the combustion chamber

1 has a grate 2 formed with a central charging port 3 opening vertically into the ash-pit 4, and the front portion of the ash-pit is formed with an opening 5 through which the fuel may be shoveled into the upper end 60 of the container. The floor line is indicated by the lines 6—6 and preferably the ash-pit has the deepened portion 7 below the floor line. The ash-pit fuel receiving opening 5 is normally closed by a suitable door which 65 need not be shown or described for the purposes of this application.

Upon the inner wall of the ash-pit and upon opposite sides thereof are secured the brackets 8 having pivots 9, upon which the 70 cylinder is rocked, this horizontal axis being preferably positioned just slightly above the floor line. The fuel container or cylinder 10 is formed with extensions 11 projecting radially downward from opposite sides 75 of the bottom of the cylinder, in the lower ends of which the pivots 9 have bearings, thus enabling the cylinder to rock into alternate registry with the grate port and the fuel receiving opening. The upper and rear 80 peripheral portion of the cylinder is formed with the curved or spherical contoured apron or follower 12, the rear end of which rests on lug 13, defining the vertical position of the cylinder and this apron functions to 85 close the grate port when it is moved from the vertical position, shown in Fig. 1, to the inclined position shown in Fig. 2.

Preferably, the apron 12 is additionally connected full length to the wall of the cylinder by the radial web 14 which also forms a convenient structure for pivotally supporting the lever mechanism which operates the piston.

The inner surface of the cylinder and its 95 extensions 11 are formed with the key seats or guides 15 extending parallel with the axis of the cylinder, and also radially with relation to the horizontal axis on which the cylinder rocks. The piston 16 is relatively 100 thin, and its periphery is formed with the downwardly extending flanges 17, formed with the keys 18 extended below the piston and fitting into the key seats 15. This key seat arrangement preferably extends radially to the arc of cylinder swing, and holds the piston rigidly and accurately at 105 right angles to the axis of the cylinder throughout the piston movement when the cylinder is moved to either of its alternate 110

positions. Also, this axially extended key-seat provision enables the use of a relatively thin piston, which is desirable when slack or pulverized coal is to be used, as a 5 piston thick enough to prevent tilting would involve too great dimensions of bearing surfaces, and fine fuel working in between the peripheral portions of the piston and cylinder would cause binding.

10 Pivotedly mounted on the web 14 is a rocking lever-type piston rod comprising a rock shaft 19 to which is fixed a lever 20 extending radially toward the piston center, the inner end being pivoted to link 21, which 15 in turn has its upper end hinged centrally to the under side of the piston.

Fixed to a portion of the rock shaft 19 is a rock arm 23 the lower end of which is carried to one side of the cylinder, the lower 20 end of the arm 23 being pivoted to the operating link or bar 24 extending horizontally out through the ash-pit, the position of this bar 24 relative to the cylinder when rocked to its forward position, is 25 shown in Fig. 2. The cylinder is rocked by means of a link 25, also extending horizontally out through the ash-pit, on the same side of the cylinder as bar 24, in order that the outer ends may be so adjacently disposed 30 as to be compactly connected with the operating mechanism in front of the ash-pit and preferably to one side of the ash-pit opening. The tilting link 25 is pivotally connected to the cylinder and to a rocker element 35 or tilting plate 26. Said plate is pivoted at 27, on a base extension 28, and is provided with a handle socket for receiving the tilting handle 29. 31 represents a fulcrum pin which is secured in the tilting 40 plate and projects through an elongated slot 30 in the toothed ratchet bar 24, thereby serving as a support and guide for the outer end thereof.

Loosely pivoted on the fulcrum pin 31, between the tilting plate and the ratchet bar 45 is an oscillatory actuator member or pawl carrying plate 32, which is provided with a socket receiving a charging handle 22. Pivoted on this plate above and below the 50 ratchet bar are a pair of actuating pawls or ratchet elements 33, 34, which engage the upper and lower toothed edges 35, 36 of said bar. The pawl 33 is a gravity pawl and the pawl 34 is provided with a pin 38, which 55 projects through a slot 39 formed in the forward arm of a release lever 37. Said release lever is pivoted on the pin 31 and has a weighted arm 56 extending to the rear of its pivotal point.

60 This construction, in fact, makes the pawl 34 also a gravity pawl through a second element, (the weighted release lever). The pawl 33 has a downwardly projecting arm 42, carrying a pin 41, which is in the path 65 of movement of shoulder 40 of the release

lever 37. The release lever has a foot-plate 43 at its forward end and by an examination of Fig. 3, it will be seen that a downward pressure on the foot plate 43 will rock the release lever 37 and disengage both pawls 70 from their respective toothed edges 35, 36, of the charging bar 24. Such disengagement will permit the charger 16 to drop by gravity. To prevent the charger from dropping too rapidly, a retarding device has been 75 incorporated in connection with the release lever and consists in a brake arm 44, which is secured to the weight arm 56 of the release lever 37 and has an inturned lower end projecting beneath the ratchet bar. The lower edge of the ratchet bar adjacent the teeth is undulated and when the release lever is rocked, (see Fig. 3), the inturned end of the brake arm 44 engages these undulations, with the effect of retarding the lateral movement of the ratchet bar.

In the position shown in Fig. 1, the release lever is inoperative to trip the pawls, because as soon as it is rocked slightly, its forward end will contact with the floor-plate 50. This would partly withdraw the pawl 34, but such movement is not sufficient to bring the shoulder 42 of the release lever into contact with the pin 41 of the pawl 33 to rock said pawl unless there is sufficient free play in the parts to permit the charging handle 22 to rock backward beyond its normal position, as shown in Fig. 1, so that the normal distance between the shoulder 42 and pin 41 would be lessened. To guard 100 against this possible condition, I provide a latch lever 51, which is loosely pivoted on the base plate extension 28, at 52, and is limited in its downward movement by a pin 53, engaging the rearwardly projecting 105 arm thereof. The forward hooked end engages over a pin 54 on the pawl carrying plate 32 and retains it in its normal position. When the tilting plate 26 is rocked, the pin 54 rises into a notch 55 in the latch plate 51, which prevents the charging handle dropping forward when the pawls are tripped.

The piston operating mechanism within the ash-pit is pivotally connected to the under side of the piston and to an exterior portion of the cylinder so that it is operatively disposed between the upper end of the cylinder and the horizontal axis of the cylinder, and as the horizontal axis is close to the ground line this provision and disposition enable the piston operating and cylinder rocking mechanisms to be placed just above the floor in front of and to one side of the ash-pit opening. This is not only a 115 very compact and convenient arrangement adapted for application to household furnaces of ordinary size and structure, but it also enables all these organized operating parts to be disposed in a vertical space rep- 120 130

resented by the distance between the grate and the ground or floor line.

It will thus be seen that the invention comprises a cylinder or fuel container pivoted in 5 the ash-pit for alternate registration with the grate port, and the fuel receiving opening through the ash-pit, that there is a piston or fuel charger reciprocal in the container with lever mechanism in the ash-10 pit forming part of the piston elevating means. Exterior of the ash-pit is a main rocking element having a link connection with the container for rocking it. All of the exterior portion of the piston operating 15 means is mounted on this main rocker element 26 which operates the container. The link bar 24, connected to the piston lever mechanism within the ash-pit, has its forward ratchet end slotted and guidably sup-20 ported by the fulcrum pin 31, on this main rocker element 26, so that this ratchet bar 24 is movable with and slidable on the main rocker element. Substantially all of the ac-25 tuating mechanism for this ratchet bar operates on this pin 31 as a center, so that pin 31 constitutes, as it were, a floating pivot. This ratchet bar actuating mechanism comprises a double pawl lever and a gravity pawl re-30 lease fulcrumed on pin 31. The rocker ele-35 ment 26 swings upwardly to raise this pivot point 31, when the container is moved to fuel receiving position, and is swung downwardly close to the floor when the container is moved into registry with the grate port. 40 By reason of the formation of the floor plate 50, and its correlation to the main rocker element, the pawl release mechanism is inoperative when the pin 31 is in its lower position, that is, when the container is in regis-45 try with the grate port, because in this position it is desirable to positively prevent the possibility of tripping, or lowering the elevator, while the movement of the container to receiving position raises this pin 31 and 50 the pawl release to such a position above the floor that said release lever 37 may function for lowering the elevator, without being limited by abutment with the floor plate 50.

However, to prevent the main actuator or 55 double pawl lever 20 from loosely wabbling during the rocking and tripping movements, the latch element 40 is provided and pivotally supported on the exterior 15 and ar-60 ranged to automatically operate in the cycle of swing of the main rocker element, to engage and hold the double pawl lever, render-65 ing it substantially inoperative except when the container is alined with the grate port, in which position mainly it is desirable to elevate the piston.

It will thus be seen that there is provided a very complete and easily operated control for the container and elevator compactly organized and disposed in front of the ash-65 pit and operative upon mechanical prin-130

iples effectually preventing the malfunction-140 ing of the cylinder and piston.

This invention is susceptible, of course, to many different embodiments within the basic principles of the invention. Certain fea-70 tures of the invention disclosed herein are not claimed but constitute the subject-matter of a separate application filed simultane-ously herewith, Serial No. 91,807.

I claim:—

1. In an underfeed for furnaces having a grate formed with a fuel charging port and an ash-pit having a fuel receiving opening, the combination comprising a fuel container pivotally mounted in the ash-pit, means for 80 rocking said container into alternate registration with said port and opening, a fuel charger in the container, a charger operating lever mechanism pivotally mounted in the ash-pit to rock with the container, a link 85 pivoted to said lever mechanism and extending exterior of the ash-pit, a reciprocating lever mechanism pivoted exterior of the ash-pit, and adapted to be operatively connected with or disconnected from said link, 90 and means whereby said lever mechanism can be released from operative connection with said link only when the container is moved toward fuel receiving position.

2. In an underfeed for furnaces having a 95 grate formed with a fuel charging port and an ash-pit having a fuel receiving opening, a container pivotally mounted in the ash-pit for alternate registration with said port and opening, a charger reciprocally mounted 100 in said container, a rocking member pivoted exteriorly of the ash-pit, a link connecting said member to the container, said member being rocked upwardly to move the container to fuel receiving position, and being 105 rocked downwardly to aline the container with the grate port, a double tooth ratchet bar movable with and slidable on said member, a double pawl lever pivoted on said member for operating said ratchet bar, a 110 pawl release mechanism also mounted on said member, means rendering said pawl release inoperative when said rocking member is in its lower position, and means with-115 in the ash-pit operated by the inner end of said ratchet bar for operating the charger.

3. In an underfeed for furnaces having a 120 grate formed with a fuel charging port and an ash-pit having a fuel receiving opening, a container pivotally mounted in the ash-125 pit for alternate registration with said port and opening, a charger reciprocally mounted in said container, a rocking member pivoted exteriorly of the ash-pit, a link connecting said member to the container, said member being rocked upwardly to move the container to fuel receiving position, and being 130 rocked downwardly to aline the container with the grate port, a double tooth ratchet bar movable with and slidable on

4

said member, a double pawl lever pivoted on said member for operating said ratchet bar, a pawl release mechanism also mounted on said member, means rendering said pawl release inoperative when said rocking member is in its lower position, means operating during the rocking of said member to hold said pawl lever in position, and means within the ash-pit operated by the inner end of said ratchet bar for operating the charger.

10 4. In an underfeed for furnaces having a grate formed with a fuel charging port and an ash-pit having a fuel receiving opening, a container pivotally mounted in the ash-pit for alternate registration with said port and opening, a charger reciprocally mounted in said container, a rocking member pivoted exteriorly of the ash-pit, a link connecting said member to the container, said member being rocked upwardly to move the container to fuel receiving position, and being rocked downwardly to align the container with the grate port, a double tooth ratchet bar movable with and slidable on said member, a double pawl lever pivoted on said member for operating said ratchet bar, a pawl release mechanism also mounted on said member, means rendering said pawl release inoperative when said rocking member is in its lower position, means actuated by said pawl release to friction brake the forward movement of the ratchet bar as the elevator descends, and means within the ash-pit operated by the inner end of said ratchet bar for operating the charger.

15 5. In an underfeed for furnaces having a grate formed with a fuel charging port and ash-pit having a fuel receiving opening, the combination comprising a fuel container pivotally mounted in the ash-pit for alternate registration with said port and opening, a fuel charger slidably mounted in said container, a rocker element pivoted exteriorly of the ash-pit, a link connecting said element to the container, means within the ash-pit for operating the fuel charger, a double toothed ratchet bar connected to said means and extended exteriorly of the ash-pit, the outer end of said bar being movable with and slidable on the rocker element, an oscillatory actuator member pivoted on the rocker element, a pair of ratchet elements mounted on the actuator member adjacent the opposing toothed edges of the ratchet bar, and a gravity trip lever normally engaging one of said ratchet elements to urge it into engagement with the ratchet bar teeth and operative to disengage both of said ratchet elements when the fuel container is rocked out of registry with the grate port, and means actuated by the trip lever to friction brake the forward movement of the ratchet bar as the charger descends.

20 6. In an underfeed for furnaces having a grate formed with a fuel charging port and an ash-pit having a fuel receiving opening, a combination comprising a fuel container

pivotaly mounted in the ash-pit for alternate registration with said port and opening, a fuel charger slidably mounted in said container, a rocker element pivoted exteriorly of the ash-pit, a link connecting said element to the container, means within the ash-pit for operating the fuel charger, a double toothed ratchet bar connected to said means, and extended exteriorly of the ash-pit, the outer end of said bar being movable with and slidable on the rocker element, an oscillatory actuator member pivoted on the rocker element, a pair of ratchet elements mounted on the actuator member adjacent the opposite toothed edges of the ratchet bar, a gravity trip lever normally engaging one of said ratchet elements to urge it into engagement with the ratchet bar teeth and operative to disengage both of said ratchet elements when the fuel container is rocked out of registry with the grate port, and means operative during the rocking of the fuel container to hold the actuator member against independent movement.

25 7. In an underfeed for furnaces having a grate formed with a fuel charging port and an ash-pit having a fuel receiving opening, the combination comprising a fuel container pivotally mounted in the ash-pit for alternate registration with said port and opening, a fuel charger slidably mounted in said container, a rocker element, pivoted exteriorly of the ash-pit, a link connecting said element to the container, means within the ash-pit for operating the fuel charger, a double toothed ratchet bar connected to said means, extended exteriorly of the ash-pit, the outer end of said bar being movable with and slidable on the rocker element, an oscillatory actuator member pivoted on the rocker element, a pair of ratchet elements mounted on the actuator member adjacent the opposing toothed edges of the ratchet bar, a gravity trip lever normally engaging one of said ratchet elements to urge it into engagement with the ratchet bar teeth and operative to disengage both of said ratchet elements when the fuel container is rocked out of registry with the grate port, and means actuated by the trip lever to friction brake the forward movement of the ratchet bar as the charger descends.

30 8. In an underfeed for furnaces having a grate formed with a fuel charging port and an ash-pit having a fuel receiving opening, the combination comprising an oscillatory fuel container within the ash-pit, a fuel charger slidably mounted therein, a rocker element exterior of the ash-pit, a motion transmitting link connecting said element to the fuel container, a floating pivot carried by said element, lever mechanism within the ash-pit for moving the fuel charger, a charging bar connected to said mechanism and supported and guided

at its outer end on the floating pivot, means for intermittently translating said bar, devices for rendering said means inoperative, said devices and means being entirely supported by said pivot and oscillated about the pivotal axis of the rocker element.

9. In an underfeed for furnaces having a grate formed with a fuel charging port and an ash-pit having a fuel receiving opening, 10 the combination comprising a fuel container pivotally mounted in the ash-pit, a fuel charger in the container, operating devices exterior of the ash-pit for unitarily rocking the fuel container and charger into alternate registration with said port and opening and for independently raising the fuel 15 charger in the container through motion transmitting members extending into the ash-pit, said devices consisting of a rocker 20 element for rocking the fuel container, a ratchet feed bar guidingly supported thereon, an oscillatory actuator member journaled on the rocker element, ratchet elements supported on the actuator member 25 on opposite sides of its pivotal support for alternately engaging the opposing toothed edges of the feed bar to intermittently translate said bar to raise the fuel charger, a trip device for disengaging the ratchet elements 30 enabling a reverse movement of the feed bar and fuel charger when the fuel container is moved out of registry with the grate port, and means for locking the actuator member against independent movement 35 during the rocking and tripping operations, said means automatically releasing the actuator member when the container is moved into registry with the grate port.

10. In an underfeed for furnaces comprising a rocking container and reciprocating charger mounted in the ash-pit, means for independently operating the container and charger comprising a main rocking element pivoted exterior of the ash-pit and 45 operatively connected to the container, a bar, the outer end of which is mounted to move with and slide on said main rocking element, and the inner end of which is operatively connected to said charger, actuating mechanism for said bar mounted on 50 said rocker element and comprising means for moving said bar forward intermittently to step raise the charger, means enabling said bar to be returned, said means being rendered inoperative when the container is 55 in fuel charging position, and means operating automatically to position the bar actuating means when the main rocking element is functioned.

11. In a fuel underfeed having a grate 60 formed with a fuel charging port, a container pivotally mounted under the grate and movable into registry with said port or into fuel receiving position, a reciprocal charger in the container, a lever operatively 65 connected to the charger, a rocking actuator, parallel links, having their inner ends connected to said container and to said lever, and their outer ends connected to said rocking actuator, means on the actuator for 70 independently operating the charger link, operative for raising the charger when aligned with the grate port and rendered operative for dropping the charger when the rocking actuator is moved to fuel receiving 75 position.

12. In a fuel underfeed having a grate formed with a fuel charging port, a container pivotally mounted under the grate and movable into registry with said port or 80 into fuel receiving position, a reciprocal charger in the container, a lever operatively connected to the charger, a rocking actuator, parallel links having their inner ends connected to said container and to said lever, and their outer ends connected to said rocking actuator, means on the actuator for 85 operating the charger link to raise the charger in step movements when the container is in registry with the grate port, 90 and to drop the charger when the container is in fuel receiving position, and means controlled by said rocking actuator preventing the charger from being dropped 95 when the container is not in fuel receiving position.

13. In a fuel underfeed having a grate formed with a fuel charging port and an ash-pit wall formed with a fuel receiving opening, a container in the ash-pit movable 100 into alternate registration with said port and opening, a reciprocal charger in the container, means for shifting the container, charger operating mechanism having an actuator movable in short, reciprocal, pump-like strokes to raise the charger in definite steps, and means for disconnecting said actuator for dropping the charger, said disconnecting means being rendered operative 105 only when the container is in fuel receiving position.

In witness whereof, I hereunto subscribe my name, as attested by the two subscribing witnesses.

JOHN N. RICHARDSON.
